US00D479968S

(12) **United States Design Patent** (10) Patent No.: **US D479,968 S**
 McDonald et al. (45) Date of Patent: ** Sep. 30, 2003

(54) **ROUTER GRIP**

(75) Inventors: **Randy McDonald**, Sussex, WI (US); **Dale Borchardt**, Wind Lake, WI (US); **Troy Thorson**, Waukesha, WI (US); **Jeffrey C. Hessenberger**, Neosho, WI (US); **Christopher Berg**, Milwaukee, WI (US); **Jeffrey S. Holly**, Menomonee Falls, WI (US)

(73) Assignee: **Milwaukee Electric Tool Corporation**, Brookfield, WI (US)

(**) Term: **14 Years**

(21) Appl. No.: **29/174,703**

(22) Filed: **Jan. 23, 2003**

Related U.S. Application Data

(62) Division of application No. 29/166,687, filed on Sep. 3, 2002, and a division of application No. 09/927,448, filed on Aug. 11, 2001.

(51) **LOC (7) Cl.** **08-06**
